UNITED STATES PATENT OFFICE.

GEORGE H. BERRY, OF SHELTON, CONNECTICUT, ASSIGNOR TO INTERNATIONAL SILVER COMPANY, OF MERIDEN, CONNECTICUT, A CORPORATION OF NEW JERSEY.

DESIGN FOR A METAL ORNAMENT FOR SILVER, PLATED, OR SIMILAR WARE.

SPECIFICATION forming part of Design No. 37,439, dated May 23, 1905.

Application filed April 17, 1905. Serial No. 256,174. Term of patent 7 years.

To all whom it may concern:

Be it known that I, GEORGE H. BERRY, a citizen of the United States, residing at Shelton, in the county of Fairfield and State of Connecticut, have invented a new, original, and Ornamental Design for a Metal Ornament for Silver, Plated, or Similar Ware, of which the following is a specification, reference being had to the accompanying drawings, forming a part thereof, and in which—

Figure 1 is a top view, and Fig. 2 an upper

edge view, of a metal ornament bearing and incorporating my design.

What I claim is—

The ornamental design for a metal ornament for silver, plated and similar ware, as shown.

GEORGE H. BERRY.
